UNITED STATES PATENT OFFICE.

CHARLES HORACE MOREHEAD, OF UNION CITY, TENNESSEE.

DESIGN FOR A TRACE-FASTENER.

SPECIFICATION forming part of Design No. 34,826, dated July 23, 1901.

Application filed June 17, 1901. Serial No. 64,963. Term of patent 7 years.

To all whom it may concern:

Be it known that I, CHARLES HORACE MOREHEAD, a citizen of the United States, residing at Union City, in the county of Obion and State 5 of Tennessee, have invented and produced a new and original Design for a Trace - Fastener, of which the following is a specification.

My invention relates to a new and original design for trace-fasteners, and is shown in 10 the accompanying drawings, in which—

Figure 1 is a perspective view, and Fig. 2 a top plan view.

The leading or characteristic feature of my 15 design resides in a trace-fastener comprising a rod or strand provided with a vertically-extending bend or hump near one end and laterally or horizontally extending bends or loops near its other end, the free ends of said rod or strand being bent, respectively, in an 20 upward and a downward direction.

In the accompanying drawings the reference-numeral 1 designates one end of a rod or strand which is slightly enlarged and in configuration represents the head of a serpent, although this is not essential and does 25 not constitute an indispensable feature of the design. From the enlarged end 1 the rod or strand is bent downward, as at 2, and thence upward at 3, horizontally at 4, and again

downward at 5 to form a vertical bend or 30 hump, as shown in Fig. 1. From this vertical bend or hump the rod or strand extends rearwardly, as at 6, and thence laterally from side to side to form two short horizontally-disposed loops 7 and 8 and an intermediate 35 longer loop 9, which latter projects on that side of the rearward extension 6 opposite to the two short loops. Forming an extension of the loop 8 is a straight portion 10, terminating in a downwardly-projecting end 11. 40

As shown in the drawings, the horizontally-disposed loops 7, 8, and 9 are arranged at right angles to the vertical bend or hump.

My design presents a trace-fastener having a novel, attractive, and distinctive appearance. 45

Having thus described my invention, what I claim as new, and desire to secure by Letters Patent, is—

The design for a trace-fastener, substantially as herein shown and described. 50

In testimony whereof I have hereunto set my hand in presence of two subscribing witnesses.

CHARLES HORACE MOREHEAD.
